KNOB ATTACHING DEVICE

Otis P. Crim, Anderson, Ind.

Application March 14, 1939, Serial No. 261,815

1 Claim. (Cl. 292—354)

This invention relates to door knobs and has for an object to provide means for releasably holding a door knob to its shank without the use of the conventional screw which is prone to work loose and become lost.

A further object is to provide a device of this character which will be formed of a few strong simple and durable parts, which will be inexpensive to manufacture and which will not easily get out of order.

With the above and other objects in view the invention consists of certain novel details of construction and combinations of parts hereinafter fully described and claimed, it being understood that the various modifications may be resorted to within the scope of the appended claim without departing from the spirit or sacrificing any of the advantages of the invention.

In the accompanying drawing forming part of this specification,

Figure 1 is an end elevation of a door equipped with door knobs constructed in accordance with the invention, parts being shown in section.

Figure 2 is a plan view of the shank and a door knob secured to the shank through the medium of a spring pressed pawl.

Figure 3 is a cross sectional view taken on the line 3—3 of Figure 1.

Referring now to the drawing in which like characters of reference designate similar parts in the various views, 10 designates a door and 11 a conventional bolt and lock mechanism applied thereto. In carrying out the invention each door knob 12 is provided with a radial passage 13 which is open at its outer end and at the inner side. Lugs 14 are formed integral with the inner side of the knob and with the stem 15 of the knob and are located at opposite sides of the inner open side of the radial passage 13. The stem 15 is provided with an opening 16 near its inner end and in that side thereof with which the lugs 14 are formed. A groove 17 is formed in the last named side of the stem and extends from the opening 16 to the lower end of the radial passage 13.

A substantially Z-shaped pawl 18 is located between the lugs 14 and is pivoted at one of its elbows between the lugs through the medium of a pivot pin 19 passed through the lugs and headed up exteriorly of the lugs as shown in Figure 3. One arm of the pawl extends into the outer end of the radial passage and is flattened as shown at 20. A coil spring 21 is seated in the passage and bears against the flattened end of the pawl. The other arm of the pawl is mounted in the groove 17 of the door knob stem and has

formed integrally therewith a tooth 22 which is disposed in the opening 16 of the stem.

A spindle 23 of substantially rectangular cross section is mounted in the door lock mechanism 11 in the usual manner and is provided with longitudinal series of rack teeth 24. The tooth 22 of the pawl is adapted to engage one of the teeth on the respective end of the spindle and secure the knob to the spindle. The spring 21 releasably holds the pawl in engagement with the spindle without the use of screws or other connectors.

To apply the knob it is simply necessary to slide the knob inwardly toward the door, the tooth 22 of the pawl engaging the rack teeth and lodging in rear of one of the teeth as the knob arrives in final position against the conventional washer 25 which is sleeved on the spindle at the face plate 26 of the lock mechanism 11. To remove the knob it is simply necessary to insert a tool such as a pencil, or small screw driver into the passage 13 and press down upon the flattened end 20 of the pawl to compress the spring and swing the pawl on its pivot 19 to disengage the tooth 22 from the rack teeth of the spindle.

From the above description it is thought that the construction and operation of the invention will be fully understood without further explanation.

What is claimed is:

A door knob provided with a spindle receiving 30 stem, a spindle in said stem having rack teeth, the door knob being provided with a radially extending passage having an opening through the outer periphery of the knob and an opening through the door confronting face of the knob, 35 parallel lugs formed integrally with the door confronting face of the knob on opposite sides of said opening therein, said stem being provided near the end with a radially disposed opening, there being a longitudinal groove in the stem extending from said radially disposed opening in the stem to the lower end of said radially disposed passage in the knob, a substantially Z-shaped pawl pivoted at its outer elbow between the lugs, one arm of the pawl extending through said opening in the door confronting face of the knob and projecting into said radially disposed passage in the knob, a helical spring in said radially disposed passage bearing against said arm of the pawl, the other arm of the pawl being mounted 40 in said groove of the stem, and a tooth formed integral with the last-named arm disposed in said radial opening of the stem and held in engagement with said rack teeth of the spindle by said spring.
